AUTOMATIC PERFORATING AND SCORING RULE

Harry Orville Reinsch, Compton, Calif.

Application October 8, 1940, Serial No. 360,247

8 Claims. (Cl. 164—98)

My invention relates to a retractable rule for platen printing presses or the like of a type in which the rule may be projected above the plane of the printing type or retracted below such plane. In my invention the rule may have perforating edges to form a perforating device of the paper printed upon or may have a line ruling edge to develop a readily bendable or foldable line in the printed paper.

The purpose of having the rule retractable and extensible is that in such a rule it is necessary to have it extending beyond the plane of the type to perform its perforating or ruling function but, if permanently beyond the plane of the type it encounters the inking rollers which pass over the type and thus cause damage to such rollers whereas when the rule is retracted the rollers pass over the type without any interference from the rule. Also, another factor is that when the rule is retracted it does not receive any ink and hence does not ink the paper either at the perforations or at the folding line.

In this type of perforator or scoring rule, an object and feature of my invention is a unitary assembly of the rule, a series of stationary cam surfaces in the rule holder and complementary cam surfaces on the underside of the rule so that the rule may be elevated and a spring for retracting the rule. With this, a further feature of my invention is the employment of a rocking device preferably in the form of a bell crank pivotally mounted in the holder which, when actuated to rotate or oscillate in one direction, shifts the rule for the interengagement of the cams and thus raises the rule while sliding it transversely.

In order to secure the proper timing, my invention contemplates the use of the plunger mounted in one end portion of the rule holder which on depression acts on the bell crank, rotating this to project or extend the rule beyond the plane of the type. The reverse movement of the bell crank caused by the return movement of the rule through the action of the retraction springs again elevates the plunger. The timing device for operating the plunger according to my invention includes a platen pin which is attached to the usual thick paper employed on the platen and such pin being provided with a button positioned to engage the plunger and depress the plunger as the platen approaches the type and the rule, which as above mentioned are mounted in a chase on the base of the printing press.

A further detail feature of my invention relates to the interengaging construction of the cams on the base of the rule holder and the un-

derside of the rule which not only give adequate support to the rule at the center, but at the extreme opposite ends whereby even pressure is developed between the paper printed upon in perforating or forming a scoring line. This construction includes a series of center cams in the form of sloping teeth and has cams which may be only a single tooth at each end of the rule holder and rule, leaving a space for the retraction springs between the end and the central cam teeth.

Another feature of a modification of my invention is making the rule holder quite thin in the portion having the elevating and the sliding rule. This is of decided use for intersecting perforations or score lines made transverse and upright relative to the sheet of paper. A further feature of this construction is having the outside and the inside plates adjacent one end spaced apart a sufficient distance to accommodate a single spring which retracts the rule and also to provide sufficient room for a rocking bell crank used to give the positive motion of elevation to the rule. In this arrangement of the thin holder it is desirable to have pin and slot guides for the rule to assure a positive retraction from the elevated position to the retracted through the operation of the spring, therefore the rule has transverse inclined slots engaging pins connecting between the outside and inside plates of the holder. With this construction a further improvement is in omitting the plunger assembly and having the platen pin operate directly on the head end of the bell crank. Due to the fact that a slight rolling motion is required between the point of contact of the pin and of the head of the bell crank, my invention also comprehends an improved type of platen pin. This pin is provided with a roller, the shank of the pin being stuck in the paper employed on the platen and thus positioning the roller in the correct location to engage the head of the bell crank.

My invention is illustrated in connection with the accompanying drawings, in which:

Fig. 1 is a side elevation partly broken away taken in the direction of the arrow 1 of Fig. 2.

Fig. 2 is a plan taken in the direction of the arrow 2 of Fig. 1.

Fig. 3 is a longitudinal section on the line 3—3 of Fig. 1, this illustrating one side of the rule holder removed as well as the operating plunger being removed and illustrating the rule in side elevation and the tooth-like cam base of the holder in side elevation, the rocking bell crank also being in side elevation.

Fig. 4 is a transverse section on the line 4—4 of Fig. 3 in the direction of the arrows.

Fig. 5 is a transverse section on the line 5—5 of Fig. 3 in the direction of the arrows.

Fig. 6 is a partial illustration of a section through the press indicating the assembly of the rule with type or furniture in the chase of a press and the button pin secured to the paper on the platen.

Fig. 7 is a detail face view of the button pin.

Fig. 8 is a partial side elevation of a modified rule of a scoring type.

Fig. 9 is a side elevation partly broken away in the direction of the arrow 9 of Fig. 10 of another form of my invention.

Fig. 10 is a plan taken in the direction of the arrow 10 of Fig. 9, both views showing the rule retracted.

Fig. 11 is a partial illustration of a section through the press indicating the assembly of the rule of Figs. 9 and 10 with type or furniture in the chase of a press with my new button pin operating to raise the rule.

Fig. 12 is a side elevation taken in the direction of the arrow 12 of Fig. 13 of the platen pin employed with the construction of Figs. 9, 10 and 11.

Fig. 13 is a face elevation of the platen pin taken in the direction of the arrow 13 of Fig. 12.

Referring first to the construction of Figs. 1 to 5, the rule is designated by the numeral 11, this being of a type having serrated perforating teeth 12 on the major portion of its upper edge, such upper edge being illustrated as straight. The rule is quite thin and has parallel sides as indicated at 13. The lower edge for the major portion has cam surfaces 15 which may be considered in the form of inverted teeth in which the flat crest is indicated at 16, the flat root at 17 and the cam slope 18, this being a straight sloping line between the crest and the root all facing in the same direction. The other side of the root is formed by a transverse edge 19. There is an end cam 20 at one end having an upward slope similar to the side or rise 18. The other end has a tooth 21 with the same characteristics as the center teeth. An operating end piece 22 extends beyond the end of the perforating teeth and beyond the tooth 21 and is illustrated as having a transverse thrust surface 23 for a purpose hereunder indicated. The under edge also has two clearance recesses 24 and 25, each of which is characterized by an upward slope 26 slightly less steep than that of the cam slope 18 and by a drop edge 27 adjacent which is a perforation 28 to engage a spring.

The main portion of the rule holder 35 is formed by an outside plate 36 and an inside plate 37. The inside plate has formed integral therewith an end block 38 which block is much thicker than the plate 37. A central cam plate 40 is located between the plates 36 and 37, the assembly being together connected by transverse screws 41. All of the plates are characterized by having a bottom edge 42 on the same plane. The cam plate however has a series of cam-like teeth 45. These may be considered as having a flat root 46, a flat crest 47, a straight cam slope 48 having the same angle as the slope 18 of the cam of the rule. The root and crest are likewise connected by a transverse edge 49 for the main teeth. At one end there is a cam slope 50 to engage the cam end 20 of the rule and to cooperate with the tooth 21 there is an end tooth 51. There are also recesses 55 and 56 in the upper surface of the cam base 40 preferably having a slope as to one portion

similar to the slopes 26 and provided with a perforation 57 for a spring.

Fitted in the recesses 24 and 25 of the rule and 55 and 56 of the cam plate 40 there are two similar retraction springs 60 each having an end caught in the perforations 57 of the cam plate and 23 of the rule, thus tending to shift the rule to the left as to Fig. 3 and at the same time draw the rule down the cam surfaces until the teeth of the rule and of the cam plate interfit, thus lowering the rule to its greatest extent. In order to afford ready access to the springs the side plates 36 and 37 each have an elongated slot 65, these slots thus aligning with the recesses 55 and 56 of the cam plate 40 and 24 and 25 of the rule when the rule is in its lowermost position.

The rocker assembly 70 to mechanically shift the rule to one side and thus upwardly, includes a deep curved recess 71 in the cam plate 40 adjacent one end and in this is rotated a bell crank 72 mounted on a pintle shaft 73 which extends preferably through the two side plates 36 and 37 and through the cam plate 40. The bell crank has an upward extending pressure finger 74 which is adapted to engage and ride with a sliding contact and thrust on abutment end 23 of the rule. The opposite arm is illustrated as having a flat surface 75. This bell crank is slightly thinner than the cam plate in order to have a free oscillating motion.

The enlarged end block 38 is for the purpose of accommodating a plunger assembly 80. The block is illustrated as having a T shaped guide 81, this being in the form of a perforation from the top to the bottom and the plunger designated 82 has a shank 83 and a T head 84. This block preferably has a flat surface 85 at the top. The inside vertical surface of the block is in sliding contact at its lower portion with the cam plate 40 and thus fits closely contiguous to the rule and to the bell crank 72. A stud 86 is secured to this inside face of the plunger and fits undeneath the end piece 22 of the rule and is located to contact and engage the upper surface 75 of the lower arm of the bell crank. When the springs 60 have retracted the rule and hold this in its lowermost position, the lower arm of the bell crank reacts against the stud 86, thus elevating the plunger to the position shown in Figs. 1 and 4. When the plunger is depressed, manifestly the reaction is in the opposite direction, the stud 86 depressing the lower arm of the bell crank thus rocking this on its pintle 73, hence presenting a rocker action. The upper arm or finger 74 reacts against the abutment end 23 of the rule, thus shifting it longitudinally towards the opposite end and causing the rule to ride upwardly on the cooperative cam surfaces respectively on the upper edge of the cam 40 and on the lower edge of the rule, this motion being sufficient to bring the perforator edge of the rule above the level of the type.

In Fig. 6 is illustrated a partial part of an assembly of a press in which the base indicated at 99 forms the mounting for the type and the perforating rule assembly, which with the furniture is held in a chase, not illustrated. The type is indicated by the numeral 91 having the plane surface 92 for the upper portion of the type over which the inking roller passes and which does the printing. The platen of the press is indicated at 93 to which is attached the usual paper cover 94 forming a backing for the paper to be printed. A button pin 95 is secured to the paper. This pin may be of a number of designs suitable 75 for being caught in the paper 94. In Fig. 7 the

form illustrated includes the shank 96, resilient cross arms 97 and the pressure button 98. This button is so located that it aligns with the plunger 80 when the platen approaches the type mounted on the base, therefore the action of the press is such that when the platen and the type are separated for inking purposes, the inking rollers operate over the surface of the type, the furniture and the retracted rule manifestly without contacting the rule. The paper to be printed upon is then inserted fitting against the platen. As the platen and the type approach the button 82 therefore raising the rule to the perforated position, manifestly as the platen recedes from making the printing contact with the type, the plunger is again elevated through the medium of the retraction spring 60 and the rule retracted.

In certain types of work it is desired to score the paper being printed. Fig. 8 shows a fragment of a scoring rule designated 100. This has a longitudinal scoring edge 101 instead of the perforated edge 12 of the rule 11. The design otherwise is the same as that above described in connection with Figs. 1 to 5. Manifestly this type of scoring rule may be readily substituted for the perforating rule and operates in the same manner. In this case however as the scoring rule need not be elevated to the same height as the perforator, as it does not cut through the paper, such slight difference of projection is taken care of by the height of the button 98 and the yield of the rule being slightly depressed with engaging the paper without cutting the perforations therethrough.

Referring to the construction of the device of Figs. 9 to 11, the rule 111 has serrated perforated teeth 112 on the complete upper edge. This rule may be made quite thin and has parallel side faces 113. The lower edge has cam surfaces 115 with flat crests 116 and flat roots 117 with a connecting cam slope 118, the root and the crests being connected on the opposite sides of the slope by a transverse edge 119. The end cam 120 has an upward slope similar to the rising cams 18. At the opposite end there is a cam slope 121 similar to the other cams. An end piece 122 extends downwardly below the cam 121 and beyond the end of the perforating teeth. This has a vertical notch 123 therein extending upwardly from the lower edge. There are two upwardly inclined guide slots 124 and 125 spaced lengthwise of the cam teeth. These have parallel upper and lower edges and such edges have the same slope as the cam edges 118.

The main portion of the rule holder 135 is formed of an outside thin flat plate 136 and parallel inside plate 137. The inside plate has a laterally offset section 138, there being a lateral bend as indicated at 139. A central cam plate 140 is located between the side plates 136 and 137, the assembly being connected by transverse screws 141. All of the plates have their lower edges 142 in the same plane. The cam plate has a series of cam teeth 145. These have a flat root 146, a flat crest 147 and a straight cam slope 148, such slopes being at the same angle as the cam slopes 18 of the rule. The root and the crest are connected by a transverse edge 149 for the main teeth. At the remote end there is the cam slope 150 engaging the end cam 120 of the rule and at the opposite end an end tooth 151 cooperates with the cam 121 of the rule. There are recesses 156 and 157 on the upper edge of the cam base 140 accommodating the portion of the rule below the inclined slots 124 and 125.

Fitted in the offset section 138 there is a retraction coil spring 160 which has one end attached to an end strip 161 of the side plate 136. In this construction the spring 160 is completely enclosed as to both sides but there is a space or opening at the upper and lower edges of the plates 136 and the offset section 138. A pair of transverse pins 162 and 163 each fit in the diagonal slots 124 and 125 of the rule and are secured in the sides 136 and 137 of the rule holder. These cooperate with the action of the spring 160 as hereunder defined.

A rocker assembly 170, not particularly Figs. 9 and 11, to mechanically shift the rule to one side and thus upwardly employs a bell crank 171 pivoted on a pintle 172, such pintle being mounted in the side plate 136 and the offset section 138. The bell crank has a head arm 173 with a cam shaped upper edge and a slope towards a point. The thrust arm 174 has a thrust pin 175 secured thereto and fitting in the vertical notch 123 of the rule. This pin also projects into an arcuate slot 176 formed in the side plate 136 only. The retraction spring 160 has one end 177 caught in a perforation at the lower portion of the thrust arm 174. Adjacent the sides of the head arm 173 there is a vertical notch 180 in the side plate 136 and directly opposite a similar notch 181 in the offset section 138 of the side plate 137.

In Fig. 11 a portion of the assembly of a press indicates the base 190 with the perforating rule assembly held by suitable furniture in a chase, this being not illustrated as it is of known construction. The type also is not illustrated. The platen 193 is shown as having the usual paper cover 194 forming a backing for the paper to be printed. A platen pin 195, note particularly Figs. 11, 12 and 13, is secured to the paper in the usual manner.

This pin, note Figs. 12 and 13, has a shank 196 provided with a point. A wide plate section 197 at the upper end with parallel ears 198; between these ears is journaled a roller 199, this having journal ends 200. The prong 201 at the head of the pin and opposite the roller bites into the paper 194 thus aiding retention of the pin in the proper position.

The manner of operation and functioning of the invention of Figs. 9 through 13 is substantially as follows, it being understood that either a perforating or a scoring rule may be utilized. In the inactive position the upper edge, that is, the teeth 112 of the perforator or the edge of the scoring rule is normally slightly below the upper edges of the rule holder plates, thus when in this position the pins 162 and 163 are adjacent the upper ends of the slots 124 and 125, the spring 160 retracts the bell crank so that the stud 174 acting in the notch 123 shifts the rule to its inactive position and the co-acting movement of the slots 124 and 125 with the pins 162 and 163 force the rule downwardly. In this position the cam on the upper end of the head arm 173 of the bell crank projects slightly above the upper edges of the rule holder. This is in a position to be engaged by the roller 199 of the platen pin 195 when the base and the platen approach. The roller 199, note Fig. 11, therefore rocks the bell crank, this roller being accommodated in the notches 180 and 181 and as there is a very slight rolling movement of the roller on the cam, it is preferable to utilize a roller rather than a rigid structure on a platen pin. The depressing action of the roller on the head arm of the bell

crank shifts this crank in a counter-clockwise movement having reference to Figs. 9 and 11. The stud 175 attached to the bell crank moves in the arcuate slot 176 and also in the notch 123, thus forcing the rule to the right as shown in Fig. 9 or upwardly having reference to Fig. 11. In this motion the coacting cam edges elevate the operating edge of the rule above the upper edge of the rule holders and thus above the type for perforation or scoring of the paper being printed. On the reverse action of the displacement apart of the base and the platen 193 as the contact between the roller 199 and the cam edge of the head arm 173 of the bell crank is broken, the spring 160 in retracting the bell crank, also through the action of the stud 175 in the notch 123, shifts the rule to the left having reference to Fig. 9 and the pins 162 and 163 operating in the slots 124 and 125 retract the rule to its inactive position.

Various changes may be made in the details of the construction without departing from the spirit or scope of the invention as defined by the appended claims.

I claim:

1. A device as described comprising a rule holder, a rule mounted therein, cam means interengaging the rule and the rule holder for elevation of the rule, a retracting guide device between the rule and the rule holder to guide the rule in its retracting movement, a bell crank pivoted to the rule holder and having a cam head arm, a platen pin having a roller positioned to engage the cam head arm and rock the bell crank to actuate the rule to a projected position.

2. A perforating and scoring rule assembly in which a holder has a displaceable rule mounted therein with interacting surfaces between the rule holder and the rule, the combination of a pin and slot guide connection between the holder and the rule to guide the rule in retraction, a bell crank pivoted to the holder and having a head arm with a cam shaped surface and an operating arm with an actuating connection between such latter arm and one end of the rule, a platen pin having a roller to engage the said cam of the head arm for rocking the bell crank and hence projecting the rule to its active position.

3. In a device as described, a platen pin having a roller to engage a moving part of a rule holder and rule assembly when locked in a chase.

4. In a device as described, a platen pin having a shank, a plate section, a roller rotatably mounted on the plate section and a prong connected to the plate section on the side opposite the roller.

5. An automatic perforating and scoring rule

assembly including in combination a rule holder having a longitudinal slot at the top with a rule mounted therein for elevation displacement, sloping complementary cam surfaces on the underside of the rule and inside of the rule holder, spring means tensioned transverse of the slot to retract the rule within the slot, means mounted directly in the rule holder and actuated by the approach of a chase and platen in printing to shift the rule longitudinally against such cam surfaces and thus elevate the rule.

6. A perforating scoring rule assembly including in combination a rule holder, a rule mounted therein, a bell crank pivoted to the rule holder and having a cam head arm projecting above the upper edge of the rule holder and a thrust arm extending downwardly, a pin and slot connection between the thrust arm and the rule adapted on rocking of the bell crank to shift the rule longitudinally and means reacting between the rule and the rule holder to raise and lower the rule on its longitudinal movement.

7. A perforating and scoring rule assembly including in combination a rule holder, a displaceable rule slidably mounted therein, a bell crank pivoted to the holder adjacent one end and having a cam head arm, the rule holder having notches adjacent the cam head, a thrust arm forming part of the bell crank, a pin and slot connection between the thrust arm and the rule, cam means interengaging between the rule and the rule holder to elevate the rule, the cam head being adapted for depression by engagement by a platen pin contacting the arm and extending into the said notches, a guide pin and slot connection between the rule and the rule holder to guide the rule in a retracting movement and a spring means to urge retraction of the rule.

8. A perforating and scoring rule assembly including in combination a rule holder having a straight outside plate and a parallel inside plate, the latter plate having an offset and an offset section from the outside plate, a rule slideable longitudinally and in an upward direction between the plates, the plates being closely contiguous to the rule except for the offset section, a bell crank pintle between the outside plate and the offset section of the inside plate, a bell crank pivoted thereon having a thrust arm extending downwardly between the outside plate and the said offset section, the rule having an end part overlapping the thrust arm of the bell crank with an interengaging means to operate the rule upon rocking of the bell crank, the said offset section being substantially limited to the space necessary for the overlap of the thrust arm and the end portion of the rule.

HARRY ORVILLE REINSCH.
